UNITED STATES PATENT OFFICE.

SAMSON DAVID EISENDRATH, OF ST. PAUL, MINNESOTA.

FILTER.

SPECIFICATION forming part of Letters Patent No. 604,931, dated May 31, 1898.

Application filed October 1, 1897. Serial No. 653,739. (No model.)

To all whom it may concern:

Be it known that I, SAMSON DAVID EISENDRATH, a citizen of the United States, residing at St. Paul, Ramsey county, Minnesota, have invented certain new and useful Improvements in Filters, of which the following is a full, clear, and exact description.

This invention relates to water distribution, and more especially to faucet-filters; and the object of the same is to produce an improved filter capable of ready application to and removal from a faucet provided with proper threads, and which filter is so constructed internally that the filtering agent will not readily become clogged nor shed its particles into the filtered-water receptacle.

This object is accomplished by the construction set forth below and illustrated in the accompanying drawings, wherein—

20. Figure 1 is a central vertical section through the filter complete. Fig. 2 is a similar section with the parts of the filter slightly separated.

Referring to the said drawings, the body 25 or shell of this filter consists of two hollow hemispherical members, T being the top or upper one and B the bottom or lower. The former has exterior threads *t* around its mouth for a purpose to appear below and at its upper end is provided with an inlet-aperture I, enlarged, as at T', to form a shoulder, and interiorly threaded, as at *i*, above the same, whereby it may be screwed onto the exterior threads which usually occur on the faucet 30

35. now in general use in households. *g* is a gasket, as of leather or rubber, which is compressed between the mouth of the faucet and the shoulder T' when the faucet is screwed tightly to its support, thus preventing leakage. The lower member B is cup-shaped, as shown, and within its mouth is provided with threads *b*, adapted to engage those at the mouth of the upper member T, while just below these threads is formed an interior shoulder B', as seen. At its lower end this member has an outlet O of any suitable character.

The filter proper consists of the following parts:

50. L is a metallic ring of L-shaped cross-section, with its upright portion innermost and its foot projecting radially outward from the

lower edge thereof, said foot resting upon the shoulder B' when in place.

S' is a sheet or disk of silk. F is a similar disk of felt specially prepared for this purpose and resting on the silk S'.

S is an upper silk disk resting on the felt.

R is a plain metal ring of a size to fit closely around the upright portion of the L-shaped ring, and G is a rubber or other gasket of the same size.

In assembling the parts above described the fabric disks are placed in a pile and laid upon the upper edge of the L-shaped ring and the plain ring brought down upon their edges, so as to clamp the latter tightly to the L-ring. The whole is thus capable of being handled readily without the necessity of the operator's hands coming in actual contact with the fabric, because the filter proper is clamped tightly within a metal frame consisting of the rings R and L. This filter and its frame are then placed within the lower member B upon its shoulder B' and the gasket G laid upon the ring R, and, finally, the two members T and B are screwed together, so that the lower edge of the upper member T bears firmly down upon the gasket G and compresses the pile of disks and rings upon the shoulder B' to hold them in position and prevent leaking from the shell or around the edges of the filter proper. The device is then attached to the mouth of the faucet in a manner which will be clear. The parts can be separated, as for cleaning or repair, and again assembled in this manner.

The exact size, shape, and proportion of elements are immaterial, and some considerable change may be made without departing from the principle of my invention. For instance, one or both silks might sometimes be omitted, if preferred.

In use the water flowing in at I strikes the upper silk sheet, whereby it is spread out into a large volume, so that it passes downward through all portions of the interior rather than through one spot at the center only, and this sheet of silk also catches and holds at its edges such particles of sand, dirt, and the like as will not pass through it. The water next passes through the felt, and, finally, it passes through the lower sheet of silk, which in turn

prevents detached particles of the felt from being delivered at O. I consider both sheets of silk highly important for use in connection with a felt or fibrous sheet F for these reasons and for the further reason that the very fine mesh of the silk sheets permits the inflowing liquid to percolate through all parts thereof to the fiber rather than falling thereon at certain points, as it would if a perforated plate were used, and the lower silk sheet permits the outflowing water also to have a free exit, while preventing particles of the fiber from being detached, and therefore is of great advantage; but they also possess the additional advantages that the upper disk spreads the water over all parts of the chamber and delivers it evenly to all parts of the felt sheet, while catching particles which would otherwise injure or become embedded in the felt.

If desired, when the filter is being cleaned, either or both silk sheets can be simply inverted in place or they can be transposed the one for the other, with or without inversion, and thus is afforded a quick and ready means of cleaning the filter without necessarily boiling or replacing the silk sheets, which would be the most thorough means of cleaning.

What is claimed as new is—

1. The herein-described faucet-filter, the same comprising a shell-like body in two members of substantial cup shape, the upper having an inlet and the lower an outlet, the upper having exterior threads around its mouth, the lower having interior threads at its mouth adapted to receive those on the upper member and also having a shoulder just below said threads, a filter proper consisting of a fabric sheet removably clamped within a metal frame, the latter resting on said shoulder, and a gasket between the lower edge of the

upper member and the upper side of the filter-frame, as and for the purpose set forth.

2. In a filter, the combination with a shell-like body in two cup-shaped members detachably connected at their open edges, one member having a shoulder opposite the edge of the other member; of a filter proper consisting of two sheets of silk with an interposed sheet of felt, said sheets being held upon said shoulder by said edge, as and for the purpose set forth.

3. In a filter, the combination with a body having inlet and outlet openings respectively above and below; of a filter proper supported within such body between the openings therein and consisting of a fibrous sheet with silk sheets held close against its opposite faces, as and for the purpose set forth.

4. In a filter, the combination with a hollow body in two members of cup shape detachably connected at their open sides, one member having a shoulder opposite the edge of the other; of a filter proper consisting of a metallic ring L-shaped in cross-section with its upright portion innermost and its foot of a size to rest on said shoulder, a plain metal ring of a size to fit closely around said upright portion, and a fabric filter-sheet passing at its edges over the upright portion and clamped between it and said plain ring, the entire filter with its frame being held between said shoulder and said edge of the body members, substantially as described.

In testimony whereof I have hereunto set my hand in presence of two subscribing witnesses.

SAMSON DAVID EISENDRATH.
